UNITED STATES PATENT OFFICE.

PHILIP SIEWENIE, OF CHICAGO, ILLINOIS.

GAME.

Application filed August 14, 1924. Serial No. 732,086.

My invention belongs to that general class of devices known as games, and relates more particularly to a miniature bowling alley game or game of tenpins, particularly adapted for home or parlor use for children or adults. More particularly my improved construction relates to a combined pin setter and ball stop. The invention has among its objects the production of a device of the kind described that is simple, inexpensive, attractive, efficient and satisfactory for use wherever found applicable. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a plan view of my device in position for setting up the pins;

Fig. 2 is a top plan view showing the same set up as a back stop;

Fig. 3 is a view in elevation of the same set up as a back stop with the pins in front;

Fig. 4 is a sectional view taken substantially on line 4—4 of Fig. 1; and

Fig. 5 is a sectional view taken substantially on line 5—5 of Fig. 3.

The game of bowling or tenpins need not be described herein in detail, it being understood that the pins are set up in the desired relation and the ball or the like rolled or thrown into the same in an endeavor to knock them down. In order to set the pins up accurately and space them before bowling against them and to stop the ball and pins when thrown at the pins, I have provided a combined setter and stop.

As shown, 1 represents a plate preferably of sheet metal or the like of the desired size and gauge of material. This is provided with a flange 2 at one side and with a flange or depending prongs 3—3 at the opposite side so that when the device is used as a pin setter it may be turned down and be supported above the floor or table by the flanges 2 and 3, the flange 2 supporting the same when set up as a back stop. Plate 1 is provided with side wings 4 which are preferably flanged at the bottom as indicated at

5, corresponding with the flange 2. The wings 4 not only serve as side stops, but in addition tend to assist in supporting the device when set up as a back stop, and give the same more stability as they tend to keep the center of gravity well forward so that the device will not tip over easily when struck by a ball or marble used as the bowling ball. Plate 1 is provided with the desired number of openings 6 therein, one for each pin 8 used in the game, there generally being ten pins, although more or less may be employed if desired. As most clearly shown in Fig. 4, the plate is flanged or turned down about the holes 6 as indicated at 7 so as to facilitate the setting up of the pins. The pins may be set in loosely or even carelessly (for example, see the tilted pin in Fig. 4) but may be all brought upright and in order by merely slightly sliding the setter on its supports.

I have shown the ball 9, which may be an ordinary marble, adapted to be thrown or rolled against the pins. Using the device, the same is set substantially as shown in Figs. 1 and 4, and the pins set in the holes, after which the setter may be lifted up and set up in back, as shown in Figs. 2 and 3. Owing to the slightly rounded openings through the flanges 7, the pins while set accurately, are not tipped over easily in removing the setter. Should the ball 9 or any of the pins strike the backstop, as usually is the case, it is found that the backstop not being fixed or rigid, acts substantially as a cushion, absorbing the force of the blow and ordinarily shifting its position very slightly if at all. There is, therefore, no rebound from the backstop of the ball or the pin which has been struck, so that they do not fly back and knock down other pins.

The device is likewise compact, as well as attractive, and may be shipped or kept in a small box with the pins and ball or easily carried about. While the same may be made any desired shape, it is usually made comparatively small so that it is compact and may be easily handled, but for games on the lawn or in larger areas, the stop, pins and ball may be made larger and heavier. The regulation rules covering bowling or tenpins may be employed and the score kept in the same manner as in a large game, and, in fact, tournaments or the like may be played with a miniature set with the same

degree of skill and pleasure as in a regular game of bowling.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a game of the kind described and in combination, a plate provided with a supporting flange at one edge and with wings at opposite ends bent slightly forward provided with flanges at the bottom, said plate having a plurality of openings through the body thereof and provided with rounded flanges at the openings.

2. In a game of the kind described and in combination, a stamped sheet metal plate provided with supporting flanges and with wings at opposite ends bent slightly forward provided with flanges at the bottom edge,

said plate provided with a plurality of spaced openings through the same and flanged about the openings, a plurality of cooperating pins, and a ball.

3. In a game of the kind described and in combination, a stamped sheet metal plate provided with a flange and with integral wings at opposite ends bent slightly forward provided with flanges at the bottom edge thereof, said flanges cooperating to support the plate on any suitable object, the object being easily movable relative to the object and being provided with a plurality of spaced openings, a plurality of cooperating pins, and a ball.

4. In a game of the kind described and in combination, a stamped sheet metal plate provided with supporting flanges and provided with a plurality of spaced openings through the same, said plate being flanged around the openings, a plurality of cooperating pins, and a ball.

In testimony whereof, I have hereunto signed my name.

PHILIP SIEWENIE.
